UNITED STATES PATENT OFFICE.

THOMAS A. REID, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC-FURNACE RESISTOR SUPPORT.

Application filed January 13, 1922. Serial No. 529,004.

To all whom it may concern:

Be it known that I, THOMAS A. REID, a citizen of the United States, and a resident of Wilkinsburg, in the county of Allegheny and State of Pennsylvania, have invented a new and useful Improvement in Electric Furnace Resistor Supports, of which the following is a specification.

My invention relates to electric furnaces and particularly to electric-resistance furnaces and it has for its object to provide a relatively simple, easily assembled and disassembled heating element for an electric-resistance furnace, having adjacent portions of a resistor spaced relatively small distances apart.

In practising my invention, I provide a plurality of relatively narrow refractory members, of substantially T-shape, supported in spaced-apart relation by the walls of the furnace, each member having a plurality of slots extending laterally therethrough in the inner face of the member. Each slot has two parts, one part being relatively narrow and substantially rectangular in cross section, the other part being wider and of substantially lozenge shape in cross section. The two parts are located in reverse position relatively to each other in adjacent slots. A relatively heavy preformed resistor member, having a plurality of substantially parallel-extending end-connected convolutions is located in said slots and between and beyond the refractory members and is self-supporting therebetween. A retaining member of trapezoidal cross section is located in the wider part of each slot to hold the resistor member in proper operative position in the furnace chamber.

In the single sheet of drawings,

Figure 1 is a view, in vertical lateral cross section on the line I—I of Fig. 2, of an electric-resistance furnace in which is incorporated the device embodying my invention;

Fig. 2 is a partial longitudinal cross-sectional view thereof on the line II—II of Fig. 1;

Fig. 3 is a partial lateral cross-sectional view of the resistor-supporting member;

Fig. 4 is a partial longitudinal cross-sectional view of the member illustrated in Fig. 3, taken on the line IV—IV thereof;

Fig. 5 is a partial longitudinal cross-sectional view of the member illustrated in Fig. 3, taken on the line V—V thereof, and

Fig. 6 is a perspective view of a retaining member.

An electric-resistance furnace 11 comprises a metallic skeleton or framework 12 having a plurality of supporting members 13 suitably secured thereto. An outer lining 14 comprises a plurality of suitably shaped bricks or blocks of a heat-insulating refractory material. An inner lining 15 comprises a plurality of bricks or blocks of a suitable high-temperature-resisting refractory material, the two linings being so formed and disposed as to provide a furnace chamber 16 of any suitable or desired contour and dimensions. The inner lining 15 is built up in spaced-apart sections to provide a plurality of groups 17 therebetween, the bricks or blocks immediately adjacent the groove 17 being provided with overhanging shoulder portions 18.

A relatively narrow refractory member 19, of T-shape in lateral cross section, has its outer end located in one of the grooves 17, its inner end extending into the furnace chamber 16, the overhanging shoulder portions 18 of the lining 15 serving to hold the member 19 in its proper operative position, substantially as illustrated in the drawing. While I may make the member 19 of a single refractory member of proper or required dimensions, I may subdivide this member, as is illustrated in the roof portion of the furnace in Fig. 1 of the drawing. A plurality of laterally-extending two-part slots are formed in each of the members 19 immediately adjacent the inner face thereof. One part 21 of each of the slots is relatively narrow and of substantially rectangular form in lateral cross section while the other part 22 of each of the slots is of lozenge shape in lateral cross section. The two parts of each of the slots are located in reverse positions in the adjacent slot to permit of locating them relatively small distances apart without reducing the strength of the overhanging portions of the parts 22 of the slots which co-operate to hold the resistor member in operative position in the furnace chamber 16.

A resistor 23 comprises a relatively heavy preformed rod or bar having a plurality of substantially parallel-extending end-connected convolutions, a portion of each of the convolutions being located in one of the slots hereinbefore described and held in proper

operative position therein by means of a retaining member 24 of trapezoidal cross section located in the part 22 of each slot. The member 24 may be made of either a suitable metal or of a refractory material.

If it is desired to assemble the preformed resistor member 23 in the furnace, it is only necessary to move the resistor member laterally of the furnace so that portions thereof will be located in the slots in the refractory member 19, after which retaining members 24 may be placed in the half portions 22 of the slots by moving them longitudinally of the resistor convolutions, which will lock the resistor member in its proper operative position in the furnace chamber 16, irrespective of whether the member is located in the wall's or in the roof portion of the furnace structure.

By locating the two half slot portions 21 and 22 in reverse positions in adjacent slots, a narrow slot portion 21 is located adjacent to a wide slot portion 22 and the amount of material available for supporting the resistor member 23 is much greater than would be the case if the slots were made of substantially the same cross section throughout, necessitating the use of some form of slot similar to the slot portion 22 to permit of locating therein a retaining member. The refractory supporting members 19 may be spaced apart any suitable distance in conformity with the area of cross section of the resistor member, the main consideration being that the distance between the members 19 and the dimensions of the resistor member shall be such as to make the resistor member 23 substantially self-supporting between the supporting means 19.

This application is closely related to a pending application of O. A. Colby, Serial No. 523,212 filed December 17, 1921, and assigned to the Westinghouse Electric & Manufacturing Company. It is also closely related to an application of O. A. Colby, Serial No. 502,691, filed Sept. 23, 1921, and assigned to the Westinghouse Electric & Manufacturing Company.

While I have illustrated a specific embodiment of my invention, I desire that only such limitations shall be placed thereon as are imposed by the prior art or are specifically set forth in the appended claims.

I claim as my invention:

1. A resistor-supporting means comprising a relatively narrow refractory member having a plurality of laterally extending two-part slots therethrough, one part being of substantially rectangular shape in lateral cross section, and the other part being of substantially lozenge-shape in lateral cross section, and means located in the outer portion of said part of lozenge-shape for operatively engaging a resistor member and holding it in said slot.

2. A resistor-supporting means comprising a relatively narrow refractory member having a plurality of laterally extending two-part slots therethrough, one part being of substantially rectangular shape in lateral cross-section and the other part being of substantially lozenge-shape in lateral cross-section, and the two parts being arranged in opposite positions relatively to each other in successive slots and means located in the part of lozenge shape of said slot for retaining a resistor member in said slot.

3. A resistor-supporting means comprising a relatively narrow refractory member having a plurality of two-part slots extending laterally therethrough, one part of said slot being relatively narrow for receiving a resistor and the other part being wider for receiving a resistor and a resistor-holding means.

4. A resistor-supporting means comprising a relatively narrow refractory member having a plurality of two-part slots extending laterally therethrough, one part of each of said slots being relatively narrow and the other part being wider and having overhanging flange portions, the two parts being located in reversed positions relatively to each other in adjacent successive slots.

5. A heating element comprising a plurality of spaced-apart refractory members, each having a plurality of two-part slots extending laterally therethrough, one part of said slots being relatively narrow and the other part being wider and having overhanging flange portions, the two parts of said slots being located in reversed positions relatively to each other in adjacent slots, a relatively heavy resistor member extending between and beyond said refractory members and having portions located in said slots, and means located in said wider parts of said slots for holding said resistor member in operative position relatively to said refractory members.

6. In an electric-resistance furnace, in combination, a plurality of spaced-apart relatively narrow refractory members, each having a plurality of two-part slots extending laterally therethrough, one part of each of said slots being relatively narrow, and the other part being wider and having overhanging flange portions, the two parts of said slots being located in reversed positions relatively to each other in adjacent slots, a relatively heavy resistor preformed to comprise a plurality of substantially parallel-extending end-connected convolutions, extending through said slots, between and beyond said spaced-apart refractory members and being substantially self-supporting therebetween and therebeyond, and means located in the wider part of said slots for holding said resistor in proper operative

position relatively to said refractory members.

7. In an electric-resistance furnace, in combination, a plurality of walls enclosing a furnace chamber, a plurality of spaced-apart relatively narrow refractory members of substantially T-shape supported by said walls, each refractory member having a plurality of two-part slots extending laterally therethrough, one part of each of said slots being relatively narrow and the other part being wider and having overhanging flange portions, the two parts of said slots being located in reversed positions relatively to each other in adjacent slots, a relatively

heavy resistor preformed to comprise a plurality of substantially parallel-extending end-connected convolutions, extending through said slots, between and beyond said spaced-apart refractory members and being substantially self-supporting therebetween and therebeyond, and means located in the wider part of each of said slots for holding said resistor in proper operative position relatively to said refractory members. 20 23

In testimony whereof, I have hereunto subscribed my name this 14th day of December 1921.

THOMAS A. REID.
